(57) **CLAIM**

The ornamental the design for a ringed, compressed coaxial cable F-connector with tactile surfaces, as shown and described.

DESCRIPTION

FIG. 1 is an isometric view of a ringed, compressed coaxial cable F-connector with tactile surfaces showing my new design;

FIG. 2 is a left side view thereof, the right side views comprising a mirror image thereof;

FIG. 3 is a top plan view thereof, the bottom view comprising a mirror image thereof;

FIG. 4 is a front end view of thereof; and,

FIG. 5 is a rear end view thereof.

The internal features shown in dot-dot-dash broken lines appearing in the front and rear end views of FIGS. 3 and 4, respectively, represent unclaimed subject matter and form no part of the claimed design.
